(57) **CLAIM**

We claim the ornamental design for a mixer impeller, as shown and described.

DESCRIPTION

FIG. 1 is a perspective view of a first embodiment for a mixer impeller showing our new design;

FIG. 2 is a top view thereof;

FIG. 3 is a bottom view thereof;

FIG. 4 is a side view thereof;

FIG. 5 is a second side view thereof;

FIG. 6 is a perspective view of a second embodiment for a mixer impeller showing our new design;

FIG. 7 is a top view thereof;

FIG. 8 is a bottom view thereof;

FIG. 9 is a side view thereof and; and,

FIG. 10 is a second side view thereof.

The broken lines showing the remainder of the mixer impeller are for environmental purposes only and form no part of the claimed design.
